VOICE CURRENT AMPLIFIER FOR LONG
DISTANCE TELEPHONE LINES

Lee E. Adler, Dallas, Tex.

Application March 6, 1931, Serial No. 520,606

19 Claims. (Cl. 179—170)

This invention relates to new and useful improvements in voice current amplifiers for long distance telephone lines.

One object of the invention is to provide improved means for increasing or amplifying the volume of sound transmission in both directions on long distance telephone lines without the use of batteries, motor-generator sets or other expensive and cumbersome equipment.

10 Another object of the invention is to provide a voice current amplifier which is simple and easy to install, is inexpensive to maintain and operate, provides an adequate amount of volume increase, has the ability to perform properly at all times 15 and on multi-party lines, and is complete in itself without the need of additional balancing equipment and other auxiliary accessories.

A further object of the invention is to provide 20 a variable stabilizer for balancing the impedance and likewise the volume increase on the opposite ends of the talking line, whereby the amplifier may be balanced against any type or length of line to obtain a uniform amount of volume increase despite variations in line impedance.

25 A still further object of the invention is to provide means for holding the primary or moving circuit open except during the actual period of ringing by either operator, whereby current consumption and wear on the ringing machine or 30 source of ringing current is reduced to a minimum and efficient maintenance of the device is set up.

An important object of the invention is to provide 35 means for automatically connecting or disconnecting the amplifying apparatus in or from the telephone circuit when said amplifier is in an operative or inoperative condition.

Another object of the invention is to provide 40 an amplifier which will operate under a greater difference in line impedances than heretofore possible, together with means for inserting an artificial line or non-inductive resistance in series with the talking circuit of each intermediate bridged station in a party line, whereby the cutting in and the cutting out of the intermediate stations by removal and replacing of the receivers will not affect the impedance balance of the line, thus making for satisfactory long distance amplification on party lines.

50 Still another object of the invention is to provide a long distance telephone amplifying apparatus with the parts so constructed and arranged in units as to permit the various units to be easily disconnected for removal or renewal.

55 A construction designed to carry out the in-

vention will be hereinafter described together with other features of the invention.

The invention will be more readily understood from a reading of the following specification and by reference to the accompanying drawings in which an example of the invention is shown, and wherein:

Figure 1 is a wiring diagram of the line and stabilizer unit,

Figure 2 is a wiring diagram of the amplifier unit and power supply unit, and

Figure 3 is a wiring diagram illustrating the amplifier connected in a long distance telephone line having intermediate bridged stations.

In the drawings the numeral 10 designates a 15 connecting block by which the amplifier is connected to one end A (Figure 3) of a long distance telephone line which needs transmission amplification to increase the volume of sound sufficient for commercially good talking. The 20 other end B of the telephone line is connected to a connecting block 11. Wire leads A1 and A2 connect the block 10 with a repeating coil C. This coil is merely an insulating transformer for 25 reducing line noise or induction and is not a necessary part of the system, when a similar coil is installed in the line ahead of the amplifier for superimposing a telegraph circuit on the talking circuit, as has long been a standard practice.

30 Wires C1 and C2 lead from the coil to switch arms Da and Db of a relay D. This relay provides an automatic cut-out or by-pass of the amplifier in case of failure of the power source supplying the amplifier. The coil of this relay 35 has one end connected to a ground lead D1 and the other end connected by a wire lead D2 to a 24 volt contact Ea of a multi-plug socket E. The connection of this socket with the power supply unit will hereinafter be described.

40 A manual cut-out switch 12 is connected in the lead D2. When the relay D is not operated the switch arms Da and Db are engaged with contacts Da1 and Db1 which have leads Dac and Dbd respectively to contacts Dc1 and Dd1 of the relay D. These latter contacts are engaged by switch arms Dc and Dd which are connected by leads F1 and F2 to a repeating coil F. The coil F has lead connections B1 and B2 to the connecting block 11. Therefore, when the source 45 of power supply to the amplifier is cut off the talking circuit is from the A end of the line through the coil C, relay D and coil F to the B end of the line. When a call comes from the B end of the line the circuit is reversed. When the 50 55

repeating coils C and F are a part of the amplifier, a simplex leg or telegraph circuit may be superimposed on the talking circuit over leads C3 and F3 which tap the center of the coils. 5 These leads are attached to a connecting block 16 for connection to the telegraph circuit.

When the relay D is energized the switch arms Da, Db, Dc and Dd are actuated into engagement with contacts Da2, Db2, Dc2 and Dd2. The 10 contacts Da2 and Db2 have leads Dag and Dbg respectively to switch arms Ga and Gb of a relay G. This relay is normally de-energized with the switch arms Ga and Gb engaging contacts Ga1 and Gb1. These contacts have leads 15 GaH and GbH to the opposite ends of the coil of a relay H. The leads GaH and GbH are also connected by leads GH1 and GH2 to contacts Ka and Kb of a multi-plug socket K.

When the relay H is energized switch arms 20 Ha and Hb are actuated into engagement with contacts H1 and H2. These contacts are connected by a common lead H12 to the power supply lead D2 and the switch arms Ha and Hb have a common lead Hab to one end of the coil of a 25 normally de-energized relay L. The other end of the coil has a ground lead L1. When the relay L is energized switch arms La and Lb are actuated into engagement with contacts La1 and Lb1. These contacts are connected by wire leads 30 L3 and L4 to a connecting block 13 which is connected with a telephone ringing machine 15 (Figure 3) at the location of the amplifier. The switch arms La and Lb have leads LaD and LbD respectively to the contacts Dc2 and Dd2 of the 35 relay D.

A connecting block 14, as shown in Figure 3, is connected in series in the power circuit X of the ringing machine for normally interrupting said circuit. The block has leads L5 and L6 respectively to a contact Lc1 and a normally un- 40 actuated switch arm Lc of the relay L, whereby the operation of the relay will actuate the switch arm into engagement with the contact and complete the power circuit to the machine 45 thus operating the same. As the relay L is only operated when the A operator rings on the line, the ringing machine is likewise only operated during the period of ringing.

Therefore, when the operator at the A end of 50 the telephone line rings on the line to call the operator on the B end of the line, the ringing current passes through the repeating coil C, the energized relay D and the de-energized relay G to the coil of relay H, thereby energizing said 55 coil and closing an electric circuit from the power supply lead D2 to the coil of the relay L, thereby energizing the same. The operation of relay L causes a second ringing current to pass from the ringing machine 15 through the connecting block 13, the relay L, the relay D and the repeating coil F to the B end of the line for signalling the B operator.

The path of the voice current from A to B is 60 through the connecting block 10, coil C, relay D and relay G to the coil of relay H; but as the relay H is of the low frequency type designed to respond only to ringing currents of sixteen cycles and upward, the voice current will not energize and operate said relay. The voice current continues 65 past the relay over leads GH1 and GH2 to the contacts Ka and Kb of the multi-plug K. These contacts have leads K1 and K2 to a winding Ma and a terminal Mb of an output transformer M. This transformer is of the standard three winding type and takes the place of the more expen- 70

sive and complicated five winding "hybrid coil" heretofore used in telephone repeaters.

A winding Mc of this transformer and the terminal Mb have leads M3 and M4 to contacts Kf and Kg of the multi-plug K. These contacts have leads K6 and K7 to a repeating coil W. This coil is connected by leads W1 and W2 respectively to a variable condenser WA and a variable rheostat WB. The coil, variable condenser and variable rheostat provide an adjustable stabilizer control for setting up a variable impedance in the transformer coil Mc to match or balance the impedance in the coil Ma. By this means the amplifier may be balanced against impedance variations in telephone lines of various lengths, whereby a uniform amount of volume gain may be obtained in both directions and "singing", "howling" and "oscillation" of the vacuum tubes is eliminated.

The windings Ma and Mc of the transformer 20 M have a common lead M1 and the terminal Mb has a lead M2 to a potentiometer N. This potentiometer is for the purpose of controlling the volume of voice current passing therethrough over leads N1 and N2 to the winding Oa of an 25 input transformer O. If excessive line noise prevails from high-tension line induction or other causes an interference eliminator (not shown) may be plugged in a socket P connected in the leads M1 and M2, as shown in dotted lines in 30 Figure 2.

A winding Ob of the transformer O has a lead O1 to the grid terminal Qa of a vacuum tube Q. This vacuum tube is of the heater cathode type. A by-pass condenser Oc is connected across the 35 winding Ob to restrict the passage of currents having a higher frequency than required for intelligible voice currents. The cathode Qb of the vacuum tube has a common lead Q1 to a condenser QO and a resistor QOA. The resistor, 40 the condenser and the winding Ob of the transformer O have a common ground lead QO1. The purpose of the resistor is to make the ground of the amplifier unit negative to the winding Ob of the transformer O instead of neutral, thereby 45 eliminating the need of the "C" or grid bias battery. This completes the input circuit up to and including the grid circuit of the vacuum tube Q.

A heater or filament Qd of the tube has leads 50 Q5 and Q6 to contacts Kj and Kk of the multi-plug K. The contacts in turn have leads K10 and K11 to contacts Ec and Ed of the power unit multiplug E, whereby an electric current is supplied to the filament for heating the tube, as will 55 hereinafter be explained.

A plate Qc of the tube has a lead Q2 to a tube testing key R. An ammeter AM is connected to the key by leads AM1 and AM2, and a voltmeter VM having a ground lead VM1 is also connected to the key by a lead VM2. The key has a lead R1 to a choke coil S which is connected with a grounded reservoir condenser T. This condenser accumulates a 135 volt "storage charge". The choke coil has a lead S1 to a contact Kc of the multi-plug K, which contact has a lead K3 to a 65 135 volt contact Eb of the multi-plug socket E. The connection of this socket to the power supply unit will be hereinafter described.

A lead Q3 from the cathode Qb and a lead Q4 from the plate Qc of the tube connect the cathode and plate respectively with the winding Ud of a transformer U. An output condenser QU is connected in the lead Q4. One end of a winding Ua and a terminal Ub of the transformer U 70

have leads **K4** and **K5** respectively to contacts **Kd** and **Ke** of the multi-plug **K**. These contacts are connected by leads **VL1** and **VL2** to the opposite ends of the coil of a normally de-energized relay **V**. The leads **VL1** and **VL2** are also connected by leads **VLa** and **VLb** to contacts **La2** and **Lb2** of the relay **L**. This completes the talking circuit from the **A** to the **B** ends of the line.

As hereinbefore explained the voice current bypasses the relay **H** and continues through the multi-plug **K** and the out-put transformer winding **Ma** to the input transformer **O** where the voltage is raised. The voice currents then pass from the transformer **O** to the grid **Qa** of the vacuum tube **Q**. The voice currents, being of a rapidly varying frequency, set up amplified variations of similar frequencies in the plate **Qc** of the tube. These amplified voice currents, being barred from passing through the choke coil **S** by the impedance offered thereby, pass over the lead **Q4** through the output condenser **QU** and the transformer **Ud** to the cathode **Qb** of the tube, thus completing the amplified voice current plate circuit.

This amplified reproduction of the voice currents passes by induction from the winding **Ud** of the transformer **U** to the winding **Ua** and from said winding over leads **K4** and **K5**, **VL1** and **VL2**, to the winding of the relay **V**. The voice current then passes over leads **VLa** and **VLb** and through the unactuated switch arms **La** and **Lb** of the relay **L** and over leads **LaD** and **LbD** to the actuated switch arms **Dc** and **Db** of the relay **D**. From the relay **D** the current passes over leads **F1** and **F2**, through the repeating coil **F** and over leads **B1** and **B2** to the connecting block **11** and **B** end of the line. This completes the talking or voice current path from the **A** end of the telephone line to the **B** end of said line.

When an operator at the **B** end of the line rings an operator at the **A** end of the line, the ringing current passes through the amplifier in the opposite direction, to that of when the **A** operator rings, but in the same sequence of operation. The ringing current passes through the connecting block **11** and the repeating coil **F** to the relay **D**. If the relay **D** is not energized the ringing current will pass from the switch arms **Dc** and **Dd** over leads **Dac** and **Dbd** to the switch arms **Da** and **Db** of said relay and from the latter switch arms through the repeating coil **C** to the connecting block **10** and **A** end of the line.

If the relay **D** is energized the ringing current will pass from the relay switch arms **Dc** and **Dd** through leads **LaD** and **LbD**, the de-energized relay **L** and leads **VLa** and **VLb** to the winding of the relay **V**, thus energizing and operating the same. This relay is similar to the relay **H** and when operated has switch arms **Va** and **Vb** engaged with contacts **V1** and **V2**. These contacts are connected by a common lead **V12** to the power supply lead **D2** and the switch arms have a common lead **Vab** to one end of the coil of the relay **G**. The other end of this coil has a ground lead **G1**. When the relay **G** is operated the switch arms **Ga** and **Gb** are actuated into engagement with contacts **Ga2** and **Gb2**. These contacts are connected to the leads **L3** and **L4** of the ringing machine **15**. Therefore, when the relay **V** is operated an electric circuit is closed to the relay **G** to operate the same, whereby the second ringing current will pass from the ringing machine through the connect-

ing block **16**, leads **L3** and **L4**, the relay **G**, the relay **D** and the repeating coil **C** to the connecting block **10** and **A** end of the line.

The path of the voice current from **B** to **A** is the same as the path of the ringing current up to the relay **V**, but as the relay **V** will only respond to high frequency currents the relay **V** is not operated and the voice currents pass through the leads **VL1** and **VL2**, the contacts **Kd** and **Ke** of the multi-plug **K**, and the leads **K4** and **K5** to the winding **Ua** and the terminal **Ub** of the output transformer **U**. The impedance of the voice currents in the winding **Ua** are balanced by a corresponding impedance which is set up in a winding **Uc** through leads **U3** and **U4** which connect said winding and the terminal **Ub** respectively to multi-plug contacts **Kh** and **Ki**. These contacts are connected by leads **K8** and **K9** to a repeating coil **X** similar to the coil **W**. This coil has leads **X1** and **X2** respectively to a variable condenser **XA** and a variable rheostat **XB**, which coil, condenser and rheostat comprise an adjustable stabilizer control, as hereinbefore explained.

The balanced voice currents pass from the transformer **U** over leads **U1** and **U2** to a potentiometer **BN** which controls the volume of voice currents passing therethrough over leads **BN1** and **BN2** to the winding **BOa** of an input transformer **BO**. If excessive line noise prevails, an interference eliminator (not shown) may be plugged in a socket **BP** (shown in dotted lines) connected in the leads **U1** and **U2**. The voice currents pass by induction to the winding **BOb**, where the voltage is raised, and from said winding over a lead **BO1** to the grid **BQa** of a vacuum tube **BQ**, similar to the tube **Q**. A filament **BQd** of the tube is connected by leads **BQ5** and **BQ6** to the leads **Q5** and **Q6**, whereby an electric current is supplied to said filament for heating the tube. The winding **BOb** has a by-pass condenser **BOc**, similar to the condenser **Oc** connected thereacross. The voice currents pass from the grid through the cathode **BQb**, a lead **BQ1**, a condenser **BQO**, a resistor **BQOA** and a ground lead **BQO1** to the ground side of the winding **BOb**.

The voice currents passing through the grid and cathode of the tube set up amplified voice currents in a plate **BQc** of the tube which plate receives a 135 volt charge through a lead **BQ2**, testing key **BR**, lead **BR1** and choke coil **BS** from a grounded storage reservoir condenser **BT**. The coil is connected to the power lead **SI**. The amplified voice currents pass from the plate **BQc** through a lead **BQ4**, and an output condenser **BQU** to a winding **Md** of the output transformer **M**. From the winding the voice currents pass through a lead **BQ3** back to the cathode **BQb**, thus completing the amplified voice current plate circuit.

The amplified voice currents travelling through the winding **Md** pass by induction to the winding **Ma** and from said winding through leads **K2** and **K1**, multi-plug contacts **Kb** and **Ka**, leads **GH2** and **GH1** and leads **GbH** and **GaH** to the relay **G**. From relay **G** the voice currents pass through leads **DbG** and **DaG**, relay **D** and repeating coil **C** to the connecting block **10** and **A** end of the line.

The power supply unit consists of a transformer **Y** which has its primary winding **Ya** connected by leads **YA1** and **YA2** to a plug **18** for connection in a 110 volt, 60 cycle, single phase power circuit (not shown). Where a direct current power cir-

cult only is available, a suitable converter (not shown) may be employed to change the power circuit as desired. The transformer has three secondary windings Y_b , Y_c and Y_d . The ends 5 of the winding Y_b have leads Y_{b1} and Y_{b2} to the plates Z_a and Z_b of a rectifying tube Z for supplying 200 to 250 volt alternating current to said tube. The ends of the winding Y_c have leads Y_{c1} and Y_{c2} to the tube filament Z_c . In this 10 manner both sets of current alternations are rectified through the action of the vacuum tube, thereby producing what is generally termed "full wave rectification", which results in a pulsating direct current potential between center tap leads Y_{b3} and Y_{c3} respectively of the windings Y_b and Y_c .

These leads conduct this pulsating current to the negative and the positive ends of a voltage divider resistance Y_{bc} with the positive current 20 passing through filter choke coils Y_A and Y_B which are connected in the lead Y_{c3} . A plurality of condensers Y_C , Y_D and Y_E having leads Y_{C1} and Y_{C2} , Y_{D1} and Y_{D2} , and Y_{E1} and Y_{E2} are bridged intermediate the leads Y_{b3} and Y_{c3} 25 on opposite sides of and intermediate the coils Y_A and Y_B . These condensers and filter choke coils serve to modulate or equalize the pulsations of the rectified current into a smooth and constant uni-directional current.

30 A lead Y_{bc1} connects the negative end of the voltage divider Y_{bc} to a ground contact E_e of the multi-plug E . This contact has a common ground lead E_K to a ground terminal 19 of the line and stabilizer unit and to a ground contact KL of the multi-plug K . A lead Y_{bc2} connects a 135 volt contact on the voltage divider Y_{bc} to the contact E_b of the multi-plug E for supplying a 135 volt current over the leads K_3 and S_1 to the amplifying unit, as hereinbefore described. 35 40 A condenser Y_F is bridged between the leads Y_{bc1} and Y_{bc2} to serve as a reservoir and to eliminate any possible remaining hum in the circuit. A lead Y_{bc3} connects a 24 volt contact on the voltage divider to the contact E_a of the multi-plug E for supplying a 24 volt current to the lead D_2 45 for operating the relays of the stabilizing unit as hereinbefore described.

The secondary winding Y_d of the transformer Y has leads Y_{d1} and Y_{d2} to contacts E_c and E_d 50 of the multi-plug E for supplying electrical current through the leads K_{10} and K_{11} , Q_5 and Q_6 , and BQ_5 and BQ_6 to the filaments of the tubes in the amplifying unit, as hereinbefore described. If desired, an adjustable rheostat Y_G may be connected 55 in series in the tube filament circuit for conveniently adjusting the voltage to the quantity required by the tubes. Spare contacts E_f and E_g are provided on the multi-plug E for connection between the amplifier and power units when 60 "Pentode" or other more complex types of tubes are employed in the amplifying unit. Any desired voltage may be obtained for such tubes by means of adjustable contacts on the voltage divider Y_{bc} .

65 In long distance amplification on lines having intermediate bridged stations or party lines the impedance balance of the line is disturbed by the cutting in and out of the intermediate stations, thereby affecting the amplifications. This disturbance is minimized by connecting an artificial line or non-inductive resistance 17 (Figure 3) in 70 series with the talking circuit of each bridged station. The amount or value of this non-inductive resistance is governed by the impedance of the line between the station and the amplifier. 75

It is obvious that with this device an adequate and uniform amount of volume increase in speech transmission amplification may be had in both directions and at all times on single or multi-party lines of any type or length. Furthermore, the construction and arrangement of the parts in various units make for convenience in repair, removal or renewal and for simplicity and efficiency in installation, maintenance and operation. 10

Various changes in the size and shape of the different parts, as well as modifications and alterations, may be made within the scope of the appended claims.

Having illustrated and described a preferred 15 form of the invention, what I claim, is:

1. In a circuit amplifier for long distance telephone circuits, means adapted to be connected at an intermediate point in the telephone line circuit between stations including a stabilizing 20 unit for balancing the amplifier against impedances of the telephone circuit, a two-way amplifying unit, and an A. C. power pack unit for supplying a local source of electrical current for the operation thereof. 25

2. In a telephone circuit, a circuit amplifying device adapted to be connected in the telephone line circuit intermediate its ends, a power unit for supplying operating current to the amplifier device, and means for bridging the amplifying 30 device and connecting the telephone circuit straight through in case the power unit fails to supply the required operating current to the amplifier.

3. In a telephone circuit, a circuit amplifying 35 device adapted to be connected in the telephone line circuit intermediate its ends, a power unit for supplying operating current to the amplifier device, and means for bridging the amplifying device and connecting the telephone circuit 40 straight through in case the power unit fails comprising a relay operated from the power unit for automatically restoring the amplifier in the telephone circuit when the source of power from the power unit is restored. 45

4. In a circuit amplifier for long distance telephone circuits, means adapted to be connected at an intermediate point in the telephone line circuit between stations including a stabilizing unit for balancing the amplifier against impedances of the telephone circuit, a two-way amplifying unit, an A. C. power pack unit for supplying a local source of electrical current for the operation thereof, a ringing unit for supplying a source of 50 ringing current to lines on either one or the other side of the amplifier set, and means for rendering said ringing unit inoperative except during the period of ringing. 55

5. In a telephone circuit, an amplifier adapted 60 to be connected in the telephone line circuit intermediate its ends including a stabilizing unit, an A. C. power pack unit for supplying operating current to the amplifier, and the various units having multi-plug jack connections therebetween 65 to permit easy disconnection or connection of the various units.

6. In a circuit amplifier for long distance telephone circuits, the combination with a long distance telephone circuit, of an amplifier adapted to 70 be connected in said circuit at a local point intermediate the terminal points of the long distance circuits and including elements for amplifying the volume, a local source of power operable from a commercial electrical power circuit for ener- 75

gizing said elements, and adjustable means for balancing the line impedances.

7. A circuit amplifier as set forth in claim 6, with means for controlling the volume of amplification.

8. A circuit amplifier as set forth in claim 6, with means for connecting a ringing unit for supplying a local source of ringing current in the circuit at the amplifier, and means for normally rendering said unit inoperative except during the period of ringing through the amplifier set.

9. The combination with a long distance telephone circuit having intermediate bridged stations, of a circuit amplifier adapted to be connected in said circuit at a point intermediate the ends of the circuit, and including means for balancing the amplifier against line impedances, and means connected in series with the circuit of each intermediate bridged station for maintaining the impedance balance of the line when said intermediate stations are cut in or out of the circuit.

10. In a circuit amplifier for long distance telephone circuits, an amplifier adapted to be connected in a telephone circuit, means for balancing the amplifier against impedances of the circuit, means for controlling the volume of the amplifier, a local source of electrical current for supplying the amplifier, and means operated by said local source of electrical current for automatically disconnecting the amplifier from the telephone circuit when the local source of electrical current fails and for automatically connecting said amplifier back in the telephone circuit when the local source of current is restored.

11. A circuit amplifier as set forth in claim 10, with means for automatically connecting a local source of ringing current in the telephone circuit, said means being normally disconnected from said circuit.

12. An amplifier as set forth in claim 10, with means for restricting the passage through the amplifier of currents having a higher frequency than required for intelligible voice-currents.

13. An amplifier as set forth in claim 10, with means for transposing the local source of electrical current into a smooth, non-pulsating uni-directional current comprising a transformer power pack, rectifying and filtering devices.

14. An amplifier unit for long distance tele-

phone circuits adapted to be connected in the telephone line circuit intermediate its ends including, a stabilizing unit having adjustable means for balancing line impedances, an amplifying unit having means for controlling the volume, and an A. C. operated power unit with a rectifier and filter for supplying a local source of a substantially non-fluctuating uni-directional current to the amplifier unit.

15. In a circuit amplifier for long distance telephone circuits, a voice current amplifying element, means for supplying a source of power current thereto, means operated by the current supply means for automatically disconnecting the amplifier from the telephone circuit when the current supply means fails and for automatically connecting the amplifier back in the telephone circuit when the current supply is restored, and normally inoperative means for supplying a local source of ringing current to the telephone circuit but rendered operative during a ringing period of a telephone set connected with the telephone circuit.

16. An amplifier as set forth in claim 10, with means for transposing the local source of electrical current into a smooth, non-pulsating uni-directional current, comprising a transformer power pack, rectifying and filtering devices, and means in the amplifier set for eliminating the A. C. hum of the power unit.

17. A two-way amplifier set for long distance telephone circuits operable from an A. C. power pack unit as a local source for electric power current for the operation thereof with means in said amplifier set for eliminating the A. C. hum of the power unit.

18. A two-way amplifier set for long distance telephone circuits operable from an A. C. power pack unit as a local source for electric power current for the operation thereof, said amplifier set including reservoir condensers and choke coils to suppress the hum which would otherwise be caused by the current from the power pack.

19. A two-way voice current amplifier set for connection at an intermediate point in long distance telephone circuits having hum eliminating means therein whereby the two-way amplifier may be operated from an A. C. power pack unit as a local current supply source therefor.

LEE E. ADLER. 50
